UNITED STATES PATENT OFFICE.

OLIVER J. MILLSAPS, OF ABILENE, TEXAS.

ADJUSTABLE CAP.

Application filed June 28, 1924. Serial No. 722,997.

To all whom it may concern:

Be it known that I, OLIVER J. MILLSAPS, a citizen of the United States of America, and resident of Abilene, in the county of

5 Taylor and State of Texas, have invented certain new and useful Improvements in Adjustable Caps, of which the following is a specification.

This invention relates to caps, and particularly to novel means whereby the head size of a cap may be adjusted to increase or diminish the said size as occasion demands.

It is an object of this invention to produce 15 a cap having adjusting means, in which the said adjusting means is concealed at the back of a facing which constitutes one of the adjustable elements by which the head size is regulated.

20 It is a further object of this invention to produce an adjustable cap of the character indicated in which the fastening for securing the adjustable elements may be expeditiously manipulated to release or secure the parts after an adjustment has been attained.

It is a still further object of this invention to produce a cap having a construction effective to accomplish the result stated 30 which comprises comparatively few inexpensive parts.

With the foregoing and other objects in view, the invention consists in the details of construction, and in the arrangement 35 and combination of parts to be hereinafter more fully set forth and claimed.

In describing the invention in detail, reference will be had to the accompanying drawings forming part of this application 40 wherein like characters denote corresponding parts in the several views, and in which—

Figure 1 illustrates a view in perspective of the front of a cap showing a device embodying the invention applied thereto;

Figure 2 illustrates a sectional view thereof partly in elevation; and

Figure 3 illustrates a sectional view of the cap on a line corresponding with the 50 line 3—3 of Fig. 2.

In these drawings, 5 denotes a cap having a head band 6 which is extended to produce overlapping extensions 7 and 8 at the front of the cap, the said extensions being 55 telescopically arranged with relation to each other, as will presently appear. The ex-

tension 7 has a loop or guide 9 that is slideable on the extension 8, whereas the extension 8 has a loop or guide 10 that is slideable on the extension 7.

The cap has a suitable lining or sweat band 11 which is secured to the inner surface of the head band at the sides and back, it being shown that its ends terminate in proximity to the visor 12. The visor may 60 be secured to the cap body or crown in any suitable manner, but for the purpose of illustration, the inner edge 12' of the visor is shown as having a lap joint with the edge of the crown. A sweat band A also covers 65 the inner surface of the front of the cap and the visor has side extensions 13 and 14 that telescope between the sweat band and the head band, entering the space between the two at the front ends of the sweat band 70 11 so that when the adjustment takes place, the wings or extensions from the visor slide in the space provided for them between the sweat band and the head band, as stated.

By reference to the drawings, it will be 75 observed that the loop or guide, which in practice is in the nature of a cloth strap of the same material that is used in making the cap, is located at the sides near the ends of the visor, and it has been found 80 in practice that the friction developed by contact of the guides with the extensions and the body of the cap when the cap is on the head, serves to retain the guides. 85 against movement and retains the guides 90 in the positions in which they are adjusted to make the cap the required size for the particular user. In the instance just mentioned, the fastening 15 may be omitted, since the adjustment will be maintained, as 95 described, through the friction occasioned by the contacting parts.

The extensions 7 and 8 are telescopically positioned with relation to each other, as 100 stated, in order that the loops 9 and 10 may be moved to cause the extensions to overlap to a greater or less extent, according to the adjustment desired for the head band, and, of course, such adjustment results in drawing the rear portion of the head band toward the visor, or permitting it to move away from the visor, according to whether the extensions of the head band overlap to a greater or less degree.

As a means for securing the extensions of 110 the head band in different positions of adjustment, the extension 7 is provided with a

plurality of studs 15, each of which constitutes one element of a snap fastening by which the extensions 7 and 8 are held, as stated, in the different positions of adjustment. The extension 8 has a socket 16 secured to its inner surface and it may engage any one of the studs, according to its position after the adjustment has been accomplished, so that by simply detaching the 10 socket from a stud and moving the extensions to cause the socket to register with one of the other studs, the said socket may be secured to another stud to maintain the adjustment.

15 From an inspection of the drawing and from the foregoing description, it will be apparent that when the head band has been adjusted, there will be no creases or gathers in the material which would render the 20 wearing of the cap inconvenient, and the fastening would be concealed, so that to all appearances the cap is of the conventional type.

It will be seen too that the extensions of

the head band overlie a portion of the external surface of the cap above the visor. 25

I claim:

In an adjustable cap, a visor having rearwardly projecting extensions, means inside the cap for guiding and concealing the extensions, a body portion provided with a head band having extensions overlappingly arranged with relation to each other exteriorly of the body portion, the said extensions being of a length to terminate on 30 opposite sides of the cap near the ends of the visor, a loop on the end of each extension embracing the other extension and being slidably thereon, one of the said extensions having fastening elements on its 35 surface contiguous to the overlapping extension and the other of said extensions having a fastening element on its surface facing the first mentioned fastenings, the said fastenings being concealed by the outer of the 40 telescopic sections, substantially as described. 45

OLIVER J. MILLSAPS.
